UNITED STATES PATENT OFFICE.

HARRY HAMMOND HOWELL, OF KANSAS CITY, MISSOURI, ASSIGNOR OF ONE-HALF
TO W. H. ELLIOTT, OF TULSA, OKLAHOMA.

COMBINATION PRESSURE-VACUUM VALVE AND THIEF HATCH.

Application filed August 9, 1926. Serial No. 128,247.

This invention aims to provide, in a single structure, a means whereby access may be had to an oil tank for gaging or thieving, means whereby pressure within the tank may be relieved and a means whereby a partial vacuum within the tank may be relieved, the practice having been, heretofore, to provide a thief hatch, a pressure release, and a vacuum release, as separate articles.

10 It is within the province of the disclosure to improve generally and to enhance the utility of devices of that type to which the invention appertains.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

25 Figure 1 shows in side elevation, a device constructed in accordance with the invention;

Figure 2 is a section on the line 2—2 of Figure 1;

30 Figure 3 is a section on the line 3—3 of Figure 2.

The device includes a tubular base 1, which may be of frusto-conical form, the base being equipped at its lower end with a flange 2 adapted to receive securing elements 3 whereby the base is held on the top 4 of a tank in which oil and like products are stored. At its upper end, the base 1 has an inwardly extended and broadened rim or seat 5. The flange 2 has an extended part 6, and an up-standing ear 7 is joined integrally to the part 6, to the flange 2 and to the tubular base 1, the ear 7 having a vertically elongated slot 8.

45 The device includes a cover which is marked by the numeral 9. The cover 9 includes an outer body 10 of tubular form, a tube 11 located within the body 10 and a base 12 joining the lower end of the tube 11 with the corresponding part of the body 10, to

form an annular chamber 14 in which may be placed a weight 15, the weight being made of lead, if desired, poured hot into the chamber 14. The body 10 is supplied at its lower end with a depending apron 16 that is spaced 55 horizontally from the base 1. The bottom 12 of the cover 9 is provided in its lower surface with an annular seat 17, the walls of which converge downwardly as at 18 to cooperate with annular gaskets 19 and 20, 60 made of a suitable composition, a retaining ring 21 being located between the gaskets 19 and 20, and being beveled upon its edges to cooperate with the gaskets 19 and 20, the gaskets being wedge-shaped in cross section, 65 securing elements 22 connecting the ring or retainer 21 to the bottom 12 of the cover 9, a simple but effective means being provided, thus, for holding the gaskets 19 and 20 in place, securely but removably. The outer 70 gasket 19 engages the rim 5 of the base 1 and affords an hermetic closure at the point indicated. The body 10 of the cover 9 has a laterally projecting lug 23 provided with a recess 24 wherein is received the ear 7 of 75 the base 1. The lug 23 carries a pivot element 25 received in the slot 8 of the ear 7. The cover 9, thus, is connected to the base 1, not only for hinged or swinging movement, but for vertical right-line movement, as well. 80 The pivot element 25 is equipped at one end with a head 26 engaging one side of the lug 23. In the opposite end of the pivot element 25 there is a slot 27 across which extends a pin 28 on which is mounted the reduced U-shaped end 29 of a spring key including converging arms 30 which bear against one side of the lug 23 to hold the pivot element 25 in place.

The body 10 of the cover 9 is equipped 90 at its upper end with an inwardly extended annular lip 31 provided with upstanding bosses 32. Radial webs 33 project inwardly from the tube 11 and support a tubular guide 34, disposed within the tube 11, the guide 95 34 being supplied in its upper end with a chamber 35 and being equipped in its lower end with a reduced bore 36. A lid 37 rests on the bosses 32 and is spaced thereby from the upper end of the body 10 and from the 100

upper end of the tube 11, the lid being held on the bosses by securing elements 38. The lid 37 has a down-turned marginal rim 39.

5 A valve 40, in the form of a disk, bears against the gasket 20, the valve embodying a stem 41 slidable in the bore 36 of the guide 34. An abutment collar 42 is threaded on the upper end of the stem 41 and is received slidably in the chamber 35 of the guide 34.

10 A compression spring 43 is located in the chamber 35, about part of the stem 41, one end of the spring engaging the abutment collar 42, and the other end of the spring engaging the guide 34 at the lower end of the 15 chamber 35. The function of the spring 43 is to seat the valve 40 against the gasket 20.

A valve opening means is provided, the same being in the form of a plunger 44 mounted to slide in the lid 37, the plunger being 20 equipped at its lower end with a foot 45 bearing on the upper end of the valve stem 41, the plunger being supplied at its outer end with a button 46.

The cover 9 may be swung to open position 25 on the pivot element 25, to permit thieving through the tubular base 1. The operator can press down the stem 41 and open the valve 40, by means of the plunger 44, thereby to ease off the pressure in the tank 30 before thieving. The result is that when the cover 9 is swung to an open position, the operator is not spattered by a puff of greasy vapor. Here note that when the valve 40 is opened, as and for the purpose specified, the 35 apron 16 directs the gas and grease downwardly, and does not permit it to blow sideways upon the garments of the operator.

In the event that pressure builds up too 40 high in the tank, the cover 9 can open, either pivotally, or by vertical right-line movement, because the part 25 is received in the vertically elongated slot 8. The pressure at which the cover 9 opens, responsive to pressure within the tank, may be governed by 45 pouring more or less molten lead into the chamber 14, to form the weight 15.

When a partial vacuum is created within the tank, atmospheric pressure is restored in the tank, because the valve 40 will open 50 downwardly, the spring 43 being compressed. The effort of the spring 43, as a closing means for the valve 40, can be regulated by shifting the abutment collar 42 along the valve stem 41.

55 From the foregoing it will be obvious that the device forming the subject matter of this application comprises, in one structure, a thief hatch, a vacuum release valve, and a pressure release valve.

60 The gaskets 19 and 20 are made of yieldable material, and, consequently, there is a tight closure at all times between the gasket 19 and the rim 5, and between the gasket 20 and the valve 40: something which is not 65 attained when a metal-to-metal contact is

provided, a metal-to-metal construction being subject to temperature changes, expansion and contraction, all of which results in a leakage of vapors from the oil in the tank. The ring 21 and the securing elements 22 afford a simple means whereby the gaskets 19 and 20 may be renewed. Generally stated, the device forming the subject matter of this application, although embodying three oil tank attachments in one, costs but little more 75 than one of those attachments, when the three of them are sold separately.

As shown at 100, the wall of the seat 17 slants away from one surface of the gaskets 19 and 20, and the edges of ring 21 slant 80 away from the inner surfaces of the gaskets 19 and 20. This construction affords a space on each side of the gasket 19 and on each side of the gasket 20, to compensate for the swelling of the gaskets 19 and 20 when they 85 become saturated with oil.

What is claimed is:—

1. In an attachment for oil tanks, a tubular base, a substantially horizontal, weighted cover cooperating with the base to close it, 90 means for connecting the cover to the base for swinging movement into a fully open position at the control of an operator, and for substantially vertical right-line sliding movement to and from closed position with 95 respect to the base responsive to pressure within a tank, an inwardly opening vacuum release valve carried by the cover, and means for holding the valve yieldably in closed position.

2. In an attachment for oil tanks, a tubular base, a cover cooperating with the base to close it, means for connecting the cover movably to the base, a vacuum release valve carried by the cover, spring means for 105 closing the valve, and compressible gaskets carried by the cover, one gasket engaging the valve, and the other gasket engaging the base.

3. In an attachment for oil tanks, a tubular base, a cover hinged to the base, an inwardly opening vacuum release valve mounted on the cover, gaskets cooperating with the base and with the valve, the cover having a recess wherein the gaskets are received, an annular member in the recess, and holding the gaskets therein, and securing devices connecting the annular member with the cover.

4. In an attachment for tanks of the class 120 described, a base; a cover including an outer body, a tube within the body and a bottom joining the tube with the body to form an annular weight-receiving chamber; a lid, means for mounting the lid on the cover in. 125 spaced relation to the upper end of the body and of the tube to afford a gas outlet of which the tube forms part, an inwardly opening valve cooperating with the base, spring-operated mechanism within the tube 130

and beneath the lid for holding the valve a fully open position at the will of an operator, and for right-line movement to a 10
yieldably closed to prevent flow of gas partially open position responsive to gas
through the tube, a member mounted mov- pressure within the base and upon the valve.
ably in the lid and accessible from the out-
5 side of the lid for engaging said mechanism In testimony that I claim the foregoing as
to open the valve at the will of an operator, my own, I have hereto affixed my signature.
and a combined means for mounting the
cover on the body for swinging movement to

HARRY HAMMOND HOWELL.
